UNITED STATES PATENT OFFICE.

CHARLES S. PRICE, OF RUTHERFORD, NEW JERSEY, ASSIGNOR TO WESTERN ELECTRIC COMPANY, INCORPORATED, OF NEW YORK, N. Y., A CORPORATION OF NEW YORK.

FUSE.

1,270,867.

Specification of Letters Patent.

Patented July 2, 1918.

Application filed August 3, 1916. Serial No. 112,989.

To all whom it may concern:

Be it known that I, CHARLES S. PRICE, a citizen of the United States, residing at Rutherford, in the county of Bergen and State of New Jersey, have invented certain new and useful Improvements in Fuses, of which the following is a full, clear, concise, and exact description.

This invention relates to thermal cut-outs or fuses for electric circuits of the type in which a fusible conductor of low melting point is ruptured by the heating effect of the current passing through it whenever such current exceeds a predetermined value.

The object of this invention is to provide a fuse of relatively short length which will be efficient in operation and which will not introduce a dangerous fire hazard.

To accomplish this object the invention provides a fuse cartridge comprising a tubular sheath inclosing a fusible conductor and vented at or near one end, the fusible conductor being constructed or provided with means to insure that its rupture in operation will take place at or near the end of the sheath opposite said vent. Interposed between the rupture point of the fusible conductor and the vented end of the sheath is a porous non-conducting material, such as asbestos sleeving, which has been found to be very efficient in breaking up the arc and in absorbing and condensing the heated metal vapors generated by the vaporization of the fusible conductor.

As a further object in preventing the expulsion of heated gases and in muffling the sound of the report due to the operation of the fuse on high potentials, an additional casing is provided so arranged as to form an air chamber about a fuse cartridge, such as described above, and having vents at the end opposite to the vented end of the cartridge.

The several features of this invention may be more readily understood by reference to the accompanying drawings, wherein Figure 1 is a sectional view of a fuse in which the rupture point of the fusible conductor is definitely located at one end, and at the opposite end of the fuse, vents are provided for the expulsion of heated gases, the intervening space being filled with a porous non-conducting material. Fig. 2 is a sectional view of a fuse cartridge of the type shown

in Fig. 1, having in addition an inclosing casing vented at the end away from the vented end in the fuse cartridge.

Referring to Fig. 1 of the accompanying drawings, 1 represents a tubular sheath of insulating material, such as fiber, inclosing a fusible conductor 2, which is connected between the metal end pieces 3. These end pieces, which may be provided with nuts 4 for aid in securing the fuse in suitable mountings, are shown as spun into the insulating tube 1, but they may be fastened by any of the methods known to the art, such as by the use of pins extending through the tubes and into the end pieces, or by means of screws passing through the tube and threaded into the end pieces. Surrounding the fusible conductor for a portion of its length is a porous non-conducting non-combustible material 5. The remaining portion of the fusible conductor is surrounded by a tube 6 of insulating material, such as paper, so arranged as to provide an air space 7 about the conductor. For the insulating material 5 asbestos sleeving has been found to be very efficient. This sleeving is allowed to come in contact with the fusible conductor, and by so doing conducts away a portion of the heat generated, allowing the portion of the fusible conductor passing through the tube 6 to attain the higher temperature, and thereby determine the point of rupture. Suitable vents 8 in the sheath 1 are so located that the heated gases generated by the rupture of the fusible conductor 2 are required to pass through practically the entire length of the asbestos sleeving before being expelled, and in so doing the metallic vapors are absorbed and chilled and the arc is broken up.

Referring to Fig. 2, a fuse cartridge is used of the same general nature as that shown in Fig. 1. In addition there are provided an inclosing casing 9 of insulating material, and metal end caps 10 adapted to make contact with the end pieces 3 of the cartridge and to close the ends of the tubular casing. This casing is provided with an aperture or vent 11 at or near the end away from the vents 8 in the sheath of the fuse cartridge. This construction provides an expansion air chamber 12 for muffling the sound of the explosion resulting from sudden vaporization of the fusible conductor

and for preventing the expulsion of heated metal vapors which might constitute a dangerous fire hazard.

While the means shown heretofore described, for determining the rupturing point of the fuse consists in providing an air chamber at that point, the balance of the fusible conductor being surrounded and in intimate contact with a material which will conduct away part of the heat generated, it is of course obvious that other well-known means may be used, such, for example, as restricting the cross-section of the fusible conductor at the desired rupture point.

15 What is claimed is:

1. A protective device comprising a tubular sheath vented at or near one end, metal caps inclosing the ends of said sheath, a fusible conductor extending between said caps and means for causing the rupture of said fusible conductor at a point near the non-vented end of the sheath.
2. A protective device comprising a tubular sheath vented at or near one end, metal caps inclosing the ends of said sheath, a fusible conductor extending between said caps, means for causing the rupture of said fusible conductor at a point near the non-vented end of the sheath, and a porous non-conducting material surrounding said con-

ductor between its rupture point and said vent.

3. A protective device comprising a tubular sheath vented at or near one end, a fusible conductor therein, a non-conducting material surrounding and in intimate contact with that portion of said conductor occupying the vented end of the sheath, and a tube of insulating material surrounding but not making contact with said conductor at the non-vented end of the sheath, whereby the rupture of the fusible conductor will take place at said non-vented end.

4. The combination with a fuse cartridge comprising a tubular sheath vented at or near one end, a fusible conductor therein, a porous non-conducting material surrounding said conductor, and means for determining the rupture point of said conductor at or near the non-vented end of the sheath, of an inclosing casing larger in diameter than and surrounding said cartridge so as to form an interposed air space, said casing being vented at or near the end opposite to the vented end of said cartridge sheath.

In witness whereof, I hereunto subscribe my name this 27 day of July, A. D. 1916.

CHAS. S. PRICE.
